LADY'S STOCKING

Willy de Mond, Hollywood, Calif.

Application July 13, 1950, Serial No. 11,120

Term of patent 14 years

(Cl. D47—7)

To all whom it may concern:

Be it known that I, Willy de Mond, a citizen of the United States of America, residing at Hollywood, in the county of Los Angeles and State of California, have invented a new, original, and ornamental Design for a Lady's Stocking, of which the following is a specification, reference being had to the accompanying drawing, forming a part hereof.

The drawing is a side elevation of the lower portion of a lady's stocking of my new design.

I claim:

The ornamental design for a lady's stocking, as shown,

WILLY DE MOND.
